DESCRIPTION

FIG. 1 is a top perspective view of a telephone line noise suppressor showing my new design;

FIG. 2 is a left side elevational view thereof, the side opposite being a mirror image of that shown;

FIG. 3 is a top plan view thereof, the bottom being of the same shape, but having no design features on the surface;

FIG. 4 is a front elevational view thereof; and,

FIG. 5 is a rear elevational view thereof.
